UNITED STATES PATENT OFFICE.

FRITZ SPANIER, OF KARLSRUHE, GERMANY.

TOOTHPICK.

Application filed April 30, 1926, Serial No. 105,846, and in Germany October 31, 1925.

This invention relates to a toothpick constituted by a handle and a metal blade, having the thickness of ordinary paper and adapted to be inserted between the teeth.

5 The said blade is preferably provided with blunt serrations on one or on both its longitudinal edges. A toothpick of this variety renders it possible to clean the narrowest gaps between the teeth more easily and 10 more reliably than with toothpicks hitherto known.

Several constructional examples of the toothpick according to this invention are illustrated in the accompanying drawings in 15 which:

Figures 1 and 2 are two elevations of one construction, the toothpick being shown when not in use and when ready for use;

20 Figures 3 to 5 are details of the body and blade and Figures 6 to 8 illustrate other constructions.

The element used for cleaning the gaps between the teeth is an oblong blade *a* having the thickness of ordinary paper and 25 preferably made of stainless steel, the longitudinal edges of the blade being roughened.

In the construction shown in Figures 1 to 30 the holder is made in two sections *b* and *c* relatively rotatable about a pin *d*, the section *c* carrying the blade by pins *i*, on which the blade *a* is loosely mounted. The various elements being in the position shown in Figure 7, the blade *a*, may be removed from the section *c* and replaced by another. When the two sections are in register (Figures 3 and 4) the pins are covered and the blade is secured. The whole may be then inserted in a case *e* forming the handle so that 40 the metal blade *a* is either covered (Figure 1) or is in the position of use (Figure 2). The other end of the case is closed by a member *f*, and thus the case may be used to hold spare blades.

45 In the construction shown in Figures 6 to 8 the holder is also made in two sections *c* and *h* relatively rotatable about a pin *d* connecting these sections. The section *c* is provided with a projecting pin *i* loosely carrying the blade *a*, whereas the section *h* has an opening *k* engaging with said pin *i*. The various elements being in the position shown in Figure 10, the blade *a* may be removed from the pin *i* and replaced by an-

other. When the two sections *c* and *h* are 55 in register (Figures 6 and 7) they may be inserted so deep in a case *e*, that the blade *a* is prevented from rotation by the sidewalls of the case *e*. A husk *g* is adapted for insertion of the case *e* with the blade 60 holder in two opposite directions (Figures 6 and 7), thus covering the blade *a* (Fig. 6) or forming a handle (Fig. 7) when using the toothpick. The interior of the case *e* may be used to hold spare blades. 65

I claim:

1. A toothpick comprising a holder consisting of two sections relatively rotatable around a pin connecting said sections, a fine metal blade, having the thickness of a sheet 70 of paper and roughened edges, removably secured to one of said sections, a case having a cross section fitting to that of the two sections of the holder when in register, said case carrying the holder with the blade and 75 forming a handle when using the toothpick.

2. A toothpick comprising a holder consisting of two sections relatively rotatable around a pin connecting said sections, a fine metal blade, having the thickness of a sheet 80 of paper loosely sitting on pins of one of said sections, a case for insertion of the holder when the two sections are in register, a husk carrying said case with the holder in either of two opposite positions. 85

3. A toothpick comprising a holder consisting of two sections relatively rotatable around a pin connecting said sections, a fine metal blade, having the thickness of a sheet 90 of paper loosely sitting on one pin of one of said sections, a case for insertion of the holder when the two sections are in register, the sidewalls of said case preventing the blade from rotation around said pin, a husk carrying said case with the holder in either 95 of two opposite positions.

4. A toothpick including a holder consisting of two parts, a fine metal blade having the approximate thickness of a sheet of 100 paper interchangeably held by the parts of said holder, a case having a cross section fitting that of the two parts of the holder when in register, said case carrying said holder with the blade and forming a handle when using the toothpick. 105

In testimony whereof I affix my signature.

DR. MED. FRITZ SPANIER.
